UNITED STATES PATENT OFFICE

166,429

VISOR FOR REARVIEW MIRRORS AND THE LIKE

Arthur F. Triphahn, Chicago, Ill.

Application June 5, 1951, Serial No. 15,420

Term of patent 14 years

(Cl. D14—6)

To all whom it may concern:

Be it known that I, Arthur F. Triphahn, a citizen of the United States, residing in Chicago, in the county of Cook and State of Illinois, have invented a new, original, and ornamental Design for a Visor for Rearview Mirrors and the like, of which the following is a specification, reference being had to the accompanying drawings, forming part thereof, in which:

Fig. 1 is a perspective view of a visor for rearview mirrors and the like showing my new design;

Figs. 2 and 3 are respectively front and rear elevational views of the visor shown in Fig. 1;

Figs. 4 and 5 are respectively top plan and end elevational views of my visor; and

Fig. 6 is a bottom view thereof.

The dotted lines in the drawing are shown for illustrative purposes only.

I claim:

The ornamental design for a visor for rearview mirrors and the like, substantially as shown and described.

ARTHUR F. TRIPHAHN.
